MINING MACHINE.

Application filed March 4, 1926. Serial No. 92,154.

The invention relates to novel and useful improvements in mining machines, and more especially to such improvements in mining machines of the endless chain cutter bar type, although in its broader applications the invention is applicable to, and useful with, other types of mining machines.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a central, vertical, longitudinal section of a mining machine embodying the invention with the cutter bar broken away;

Fig. 2 is a full top plan corresponding to Fig. 1, also with the cutter bar broken away;

Fig. 3 is a side elevation of the machine shown in the preceding figures, looking at the bottom side thereof in Fig. 2 and also with the cutter bar broken away;

Fig. 4 is a vertical, transverse section, taken on the line 4—4 of Figs. 1 and 3, looking in the direction of the arrow;

Fig. 5 is the same transverse, vertical section as Fig. 4, but looking in the opposite direction, as shown by the arrows in Figs.

1 and 3;

Fig. 6 is a central, vertical, longitudinal section, with parts in elevation, of a somewhat different embodiment of the invention, including a speed reducing gear and clutch connection between the motor and cutter;

Fig. 7 is a fragmentary top plan corresponding approximately to the left-hand half of Fig. 6;

Fig. 8 is a detail, vertical, transverse section taken substantially on the line 8—8 of Fig. 7;

Fig. 9 is a top plan, with parts omitted, and others diagrammatically indicated, of the cutter bar and chain, the machine being indicated in dotted line;

Fig. 10 is a side elevation looking at the adjacent side of Fig. 9;

Fig. 11 is a transverse, vertical section taken on the line 11—11 of Fig. 9;

Fig. 12 is a transverse, vertical section taken on the line 12—12 of Fig. 9; and

Figs. 13 to 19 are diagrammatic views, illustrating different steps in, and different ways of, operating the machines.

The invention is directed to producing a kerf-cutting mining machine, which in certain features is especially adapted for use in very low coal seams; with this in view, the entire machine is of a very low, compact, yet powerful structure, which features render it especially adaptable to, and useful in, thin coal seams. The invention is further directed to producing a kerf-cutting mining machine, which in addition to having the features already described, is of very simple structure, having few parts and devoid of excess weight, is efficient and powerful, and which has means and instrumentalities whereby the machine is readily handled and maneuvered by its own power during all stages of the kerf-cutting work.

Referring now to the embodiment of the invention, illustrated by way of example in the accompanying drawings, the general structure of the motor and its mountings, and the immediately cooperating parts, will be first described. As embodied, a bed or foundation plate 1 is provided, adapted to rest upon the mine floor, and to be moved therealong, the general structure of the mining machine being either integral with or mounted upon the bed plate. Integral with and extending upwardly from the bed plate 1 (Figs. 1-5) are pillars 2 and 3, constituting journals for the hubs of the rotatable housing of the field winding of an induction motor. In the preferred form of my invention, a motor is employed in which both the field and armature rotate, as will be later more fully explained.

As embodied, the housing is provided with a central cylindrical part 10, within which

the field windings 11 are mounted, these windings being indicated merely diagrammatically, for the sake of clearness, and they may be of any known or suitable form. At either side of this central part 10, the housing is of reduced diameter.

On one side this reduced cylindrical portion constitutes a cable-winding drum 12, which drum constitutes part of the mechanism for driving or progressing the machine to the work during the kerf-cutting, the side face 13 of the central part 10 of the housing forming one flange of drum 12, and a flange 14 being formed at the exterior flat face of the part 12. A bearing for this end of the entire housing structure is provided. Externally to the drum 12, and integral with, and extending outwardly from, the flat side face thereof, is a hollow, cylindrical hub 16, which is journaled to rotate in the bearing upon the pillar 3, a friction sleeve 17 being interposed between the hub and the bearing.

Frictionally acting means to control the rotation of the field winding housing and the cable winding drum 12 are provided. As embodied, on the opposite side of the part 10 of the field winding housing, is a cylindrical part 28 of lesser diameter, and constituting a brake-drum, whereby the frictional, retarding force may be applied to the field winding housing and cable drum for purposes later to be more fully described. The flat face 29 of the part 10 for the housing constitutes one flange of the brake drum, and there is a flange 30 formed on the other side of the cylindrical drum face. Externally to the drum 28, the housing extends outwardly in an integral, hollow hub 31, which is journaled in the bearing upon the pillar 2 of the base plate 1 of the machine. A friction sleeve 32 is provided between the hub 31 and its bearing. The hubs 16 and 31 thus constitute concentric bearings for the field winding and its housing, and for the cable-winding drum at one side thereof, and the brake drum at the other side thereof.

A part of the means for directing and maneuvering the machine is conveniently mounted at this part of the structure, and will therefore be now described. It consists essentially of a loosely rotating cable drum, on which is wound a cable having its end anchored, and of a brake-drum for controlling the rotation of the otherwise freely rotating cable drum. As embodied, there is mounted on an extension of the hollow hub 31 of the field-winding housing, extending beyond the bearing 2, a combined cable winding and brake drum, the drum being freely rotatable on the hub 31. This drum has a body 38 loosely mounted on the sleeve 32, which also projects outwardly around the hub 31. A retaining device is applied to the end of the hub, comprising a screw-threaded body 39, screwing into an interior thread in

the hollow hub 31, having a flanged cap 40 fitting over the external end face of the hollow hub 31, and having a squared turning head 41 on the exterior. This device serves to keep the drum 38 in position, and also to retain a lubricant within the hub.

The drum 38 is provided with an exterior flange 45, and an intermediate flange 46, the cable 47 being wound on the drum intermediate of these two flanges. The drum is also provided with a flange 51, and there is a brake band 52 operating upon the cylindrical surface of this part of the drum 38 between the flanges 46 and 51.

Means are provided for varying the tension of the brake band 52, and for maintaining the brake band at any desired adjusted tension. As embodied (Figs. 1 to 4), one end of the brake band 52 is pivoted at 56 to the inner end of a forked lever 57, which lever is pivoted at 58 on an extension of the cap plate 66 of the bearing 2. The other end of the brake band 52 is pivoted at 59 to the lever 57, on the opposite side of the pivot point 58 from the other end 56 of the brake band.

The outer end of the lever 57 is apertured to receive a screw-threaded bolt 60, the bolt 60 also passing through an aperture in the horizontal reach 61 of a standard having also vertical reaches 62 and 63, mounted on the bed plate 1 of the machine. The head 64 of the bolt 60 is beneath the horizontal reach 61 of the holding bracket, and a wing nut 65 is screw-threaded onto the bolt 60. Thus the tension of the brake band 52 on the drum 38 may be regulated, and the resistance to paying out the cable 47 may be varied as desired.

The motor armature 80 is only indicated conventionally, for the sake of clearness, and it may be of any known or other suitable form. The armature shaft 81 (Figs. 1-6) is provided at the left-hand end in Fig. 1 with a shouldered and reduced portion 82, this portion 82 being journaled in a deep-groove, thrust ball-bearing 83, which bearing is seated against a shoulder 84 formed in the interior of the hollow hub 31 of the field winding housing. A reduced end 85 of the shaft 81 is screw-threaded, and a nut 86 is screwed thereon, to retain the parts in position.

On the opposite side of the armature is a like bearing, there being a reduced part 89 of the armature shaft 81 journaled in a deep groove, thrust ball-bearing 90, which bearing is seated in the interior of the hollow hub 16 of the field winding housing, against a shoulder 91 formed in the interior of the hub. The right-hand end of the armature shaft 81 has a reduced portion 93, extending out a considerable distance from the reduced portion 89, to constitute a drive for the kerf-cutter mechanism. A nut 94

is screw-threaded on the part 93 of the shaft up against the ball bearing 90 to retain the parts in position.

Referring now to the driving connections 5 for the kerf cutter, and certain other mechanisms, a beveled pinion 95 is fixed on the exterior end of the projecting part 93 of the armature shaft, and the pinion is preferably pinned on the shaft. A nut 96 is also 10 shown screwed on the end of the shaft to hold the parts in position.

The electrical connections for the motor may be of any known or suitable form, and are shown only in a general way. As so 15 shown, an insulated conductor ring 106 is carried in the face of the brake drum 28 of the field winding housing. A brush 107 is in contact with the ring 106, and connects with a power supplying cable 108, the parts 20 being protected by a casing 109.

Referring now to the details of the embodied driving mechanism for the kerf cutter, and for progressing the machine to the work as the cutting advances (Figs. 1 to 5), 25 a beveled gear 117 meshes with the pinion 95, the gear having a long hub 118. This hub rests on a friction washer 119, the washer resting upon a bearing sleeve 120 formed in a flat web 121 integral with the 30 pillar 3, and with an end support 122, which is likewise integral with the machine frame, these parts being portions of a housing about the driving mechanism. The hub 118 is also provided with a radial thrust ball- 35 bearing 129, which is mounted in a seat 130 formed in the inner part of a cap plate 131, which plate forms the upper part of the housing for the driving mechanism. Plate 131 has a flange 132 seated on a like flange 40 133 formed on an upwardly extending side wall portion 134 of the housing, integral with the flat part 121 of the machine frame and integral with, or fastened to, the bed plate 1.

The hub 118 extends upwardly through the cap plate 131, and exteriorly thereto it is keyed to a horizontally-disposed brake- 45 drum 141, which has a downwardly-extending hub, which rests and rotates upon a hub 143, formed on the upper face of the cap plate 131. The hub 118 of the bevel wheel 50 is keyed to the drum brake 141 by a suitable key 144.

Within the hub 118, but not directly connected thereto is a vertical cutter-chain driving shaft 157, there being sleeves 158, 159 and 160 between the hub 118, the hub 120, and the shaft 157. At its upper end shaft 157 has fixed thereto by suitable key 168, 55 a power connecting and disconnecting disc or plate 167. A fastening bolt 169 is screwed into the head of the shaft 157 to hold the connecting and disconnecting disc 167 in longitudinal position. The disc 60 167 is provided with a downwardly-depend-

ing hub, which is carried upon a ball-bearing 170, which bearing rests upon the top face of the hub of the brake drum 141.

Means are provided for connecting and disconnecting the brake drum 141 and the 70 disc 167, and therewith connecting and disconnecting the cutter-chain driving shaft 157 and the bevel gear 117, which in turn is driven from the motor armature 81. As embodied, the disc 167 is provided with a 75 horizontally-disposed, exterior flange 173 parallel with, and closely contiguous to the face of the brake drum 141. In the flange 173 are formed a plurality of apertures 174, and corresponding apertures 175 are formed 80 in the flat face of the brake drum 141. A suitable device is employed for connecting together and disconnecting the drum 141 and the disc 167, such as the U-shape member 176 (Figs. 1 and 2), which may be inserted into adjacent apertures in the disc and drum, to cause them to rotate together. Member 176 may be engaged by the central portion and lifted out from the apertures, thereby disconnecting the disc 167 and the 90 drum 141, so that the shaft 157, and consequently the kerf cutting mechanism are 95 mechanically disconnected from the motor.

Referring now to the particular form of 95 kerf-cutting mechanism herein exemplarily employed and illustrated, a guide bar 191 is employed, having a mounting in the machine frame, as best shown in Figs. 1 and 9. The inner end of the bar fits into a horizontally-disposed recess, formed in the base of 100 the machine between the bottom plate 1, a top plate 192 and side plate 193. The bar is provided at this inner end with slots 194 and 195, and bolts 196 and 197 pass through the top plate 192, and the bottom plate 1, 105 and through the slots 194 and 195, to maintain the cutter bar in position.

To maintain the cutter bar 191 against endwise displacement a plurality of apertures 199 are provided in the bar contiguous 110 to the outer end of the bed plate of the machine, and a pin 200 is driven into the hole 199 which happens to come in register with the end edge of the bed plate. This pin thus takes up the end thrust on the bar and conveys it directly to the bed plate of the 115 machine.

The cutter bar is provided along its edges with guides 203 and 204, along which the 120 flexible chain cutter 205 runs, the chain being provided with teeth 206. This structure may be of any suitable or known form and need not be described in detail. At its inner end, the cutter chain runs over a sprocket wheel 207, fixed to shaft 157 by a key 208, 125 the cutter chain being thus driven from the shaft 157, and thereby from the armature shaft 81.

Means are provided by the invention for 130 regulating the action of the motor on the

cutter bar, and the relative action of the cutter bar mechanism and of the means for advancing the machine to the work as the kerf is cut. In the embodied form thereof, this is effected, in part at least, by the action of the brake mechanism of the brake drums 28 and 141. The action of the brake drum 28 is exerted directly upon the field winding housing, and the action of the brake drum 141 may be exerted on the motor armature either when the load of the kerf cutting chain is thereon, or when it is disconnected therefrom.

Referring now to the control for the brake drum 28, a brake band 218 is provided (Figs. 1, 2, 3 and 5) cooperating with the drum. One end of the band 218 is pivotally connected at 219 to a forked lever 220, which lever is pivoted at 222 to an extension 223 of the bearing cap 217 of bearing 3. The other end of the brake band 218 is pivotally connected at 224 to the lever 220 at the other side of its pivot bearing 222 from the pivotal connection 219 for the other end of the brake band. In the exterior end of the lever 220 is an aperture through which projects a bolt 225, which bolt also extends through an aperture in the horizontal reach 61 of the bracket already described, with the head 226 of the bolt resting against the underside of the bracket. A wing nut 227, or other suitable regulating device, is screwed on the bolt 225, and thus the action of the brake band 218 on the drum 28 may be nicely and continuously regulated.

Referring now to the regulating means for the brake drum 141, it will be recalled that this may be used in connection with the connecting and disconnecting mechanisms for the brake drum and disc 167. In the embodied form of said means, a brake band 239 cooperates with the brake drum 141 (Figs. 1, 2, 3 and 5), one end of the brake band 239 being pivoted at 240 to a pin forming part of a lever 241. This lever comprises two parallel plates connected to, spaced apart by a hub at its pivot point (Figs. 3 and 5). The pin 240 is fixed in both side plates of the lever. The lever 241 is pivotally mounted at its apertured hub 242 on a pin extending upwardly from a seat 243 formed on the housing cap plate 131.

The other end of the brake band 239 is pivoted at 244 to another pin, mounted in both of the side plates of the lever 241, and located on the opposite side of the hub and pivot point 242 of the lever from the other end 240 of the brake band. Pivotally connected to the outer end of the lever 241 is a link 245, which link is pivoted at 246 to a lever 247, which in turn is pivotally mounted at 248 on the machine frame. Thus, by moving lever 247 the frictional action of brake band 239 on drum 141 may be regulated as desired. Suitable means are pro-

vided for holding the lever 247 in any position to which it may be moved to effect or vary the action of the brake band 239 upon the drum 141.

A plurality of guiding sheaves for the cables *a* and *b* on the drums 12 and 38 are provided at suitable locations, and are indicated in the drawings by reference numerals 250 to 258. There is shown in Fig. 9 a sheave 259 mounted on, and at or near the exterior end of, the chain cutter bar.

The operation of the machine in so far as described may be first stated in a general way, and particular applications thereof will be more fully illustrated from the diagrams of Figs. 13 to 19 of the drawing. For such general description, the machine may be assumed as being operated, the cutter bar being driven from the motor by reason of the member 176 connecting disc 167 with brake drum 141. As the machine operates, the armature 80 will rotate in one direction, and the field windings 11 and the housing therefor in the opposite direction.

The armature, through pinion 95 and gear wheel 117, brake drum 141, disc 167 and shaft 157, will drive the cutter chain. At the same time, the rotation of the field winding housing in the opposite direction will wind the cable *a* onto the drum 12 to progress the machine forwardly and hold the cutter to the work as it cuts the kerf. Should the cutting be easy, and, therefore, rapid, by applying the brake band 239 to a desired degree to the brake drum 141, greater resistance or load is put upon the armature, and the tendency to rotation or torque of the field winding housing is increased, the cable *a* will be wound on the drum 12 more rapidly, and the machine will be advanced faster into the work.

By releasing the brake drum 239, the speed of the cutter relatively to the advancing cable will be increased, and the machine thereby adjusted to advance slowly with a relatively high speed of the cutter chain, as in work when the cutting is hard and consequently slower.

If the connecting link 176 is removed, the driving connection between the armature 80 and the cutter bar is disconnected. If now the brake band 239 be tightened on the brake drum 141, a load is thrown on the armature, and this will result in imposing a torque in the opposite direction upon the field winding housing, and the cable will be wound on the drum 12 to progress the machine along the floor or support without operating the kerf cutting mechanism.

The drum 38 is employed for directive purposes, as this drum is loose on its mounting. The cable *b* is arranged to be paid out from the drum, the paying out, or the rate of paying out, being controlled and determined by the action of the brake band 52 on the brake drum. The exterior end of the cable

is anchored to some fixed point such as a jack-post, and if the rear end of the machine is moving too slowly and tending to throw the machine out of alignment, the wing nut 65 would be slightly unscrewed, thus tending to permit freer paying out of the cable 47, and the machine would be brought into alignment as desired for cutting. In case the rear end of the machine were traveling too freely and thereby tending to move out of alignment in the opposite direction, the wing nut 65 would be screwed down, the brake band 52 would be tightened and the tendency of the drum 38 to rotate would be lessened and again the cable would tend to correct the position of the machine. Further exemplary explanation of the uses of these devices will be provided in connection with the diagrammatic figures.

In the exemplary embodiment already described, the means for progressing the machine and holding it to the work has been shown mounted directly on the field winding housing and rotating directly therewith. In practical operations, however, it will usually be found advisable to have a speed-reduction gearing interposed between the housing and the winding cable, and it will usually be found necessary or convenient also to employ a clutch mechanism for throwing in and out the machine progressing mechanism.

In Figs. 6, 7 and 8 there is shown an exemplary embodiment of such mechanism. The parts of the mechanism corresponding to those precedingly described will not be referred to again, but the same reference numerals will be applied thereto. In this embodiment also, as a matter of convenience in design, the relative position of the two winding cables *a* and *b* has been reversed, the positively wound cable being shown at the left hand end in Fig. 6 and the paying-off cable at the right hand end, whereas, the reverse is the case in the form shown in Figs. 1 to 3. The explanation previously given as to the coaction of the cables in progressing and steering the machine, will be understood as being correspondingly modified for this changed structure, and will be clear without further elaboration.

Referring now to the speed-reduction and clutch mechanism in the form shown in Figs. 6 to 8, the hub 31 terminates at the outside of bearing 2. The end of the hub is provided with a flat end plate 271. Fixed concentrically in the plate 271 is one end of a shaft 272, the shaft projecting therefrom, and the other end thereof being journaled in a sleeve 273. This sleeve is journaled in a bearing 274, formed in a pillar 275, extending upwardly from the bed plate 1 of the machine.

Fixed to shaft 272 are plate elements 276 of a friction disc clutch mechanism, by means of a key 277. The cooperating plates 278 of the disc clutch are fixed to a housing

or casing 279, which housing has integral therewith a sleeve 280 encircling the friction sleeve 273. Integral with, or fixed on, the sleeve 280 is a worm 281, whereby the worm 281 rotates with the plates 278 when they are driven from the plates 276.

The clutch actuating and controlling means comprises a disc 282, adapted to contact on its side face with the exterior friction disc 278. Disc 282 is integral with a sleeve 283, which loosely encircles, and is slideable along shaft 272. Sleeve 283 is provided with an exterior annular groove 284, and a compression spring 285 impels the disc 282 into strong frictional engagement with the clutch disc. A controlling lever 288 is pivotally mounted at 289 on the machine frame, and has a pin 290 projecting into the slot 284, whereby the clutch may be thrown in and out. Suitable means for retaining the lever 288 in any desired position may be provided, but are omitted for the sake of clearness.

In mesh with worm 281 is a worm wheel 299, fixed to a vertically-disposed shaft 300 by means of a key 301. Shaft 300 is journaled at its upper end in a horizontal extension 302 of a bracket 303, fixed to, and extending upwardly from, the bed plate 1 of the machine. Fixed also to shaft 300 by key 304 is a drum 305 upon which is wound a cable *a'*, this cable corresponding to the cable *a* in the structure shown in Figs. 1 to 5. Drum 305 has flanges 306 and 307, and its bottom end face rests on a hub-like seat on the bed plate.

Thus there is provided any desired speed reduction between the motor field housing, and the winding drum for winding or progressing the machine forwardly and holding the kerf cutting bar to the work as the cutting progresses.

In Figs. 13 to 19 there are illustrated exemplarily and diagrammatically certain ways of moving and using the machine, utilizing the motor, the cable drums, cables, and brakes, and properly located jack-posts. In Fig. 13 the mining machine is shown being drawn into a room, by winding the cable *a* onto the drum 12, the cable being reeved along certain of the sheaves 253-258 as shown, the cable being attached to a jack post *j*. The cutter bar is, of course, disconnected from its drive. In like manner the machine may wind itself onto a mining machine carrier.

In Fig. 14 the machine is shown being swung around in the direction of the arrow to bring the cutter bar up to the face of the room. As shown, the cable *a* is reeved past one of the sheaves on the body of the machine, and around the sheave 259 on the cutter bar, and the machine will be thereby moved from the position of Fig. 14 to that of Fig. 15, the cable being rearranged about

the sheaves, in the meantime, and at the proper position in the turning operation.

Fig. 15 shows the machine with the cutter bar pointed into one corner of the face and rim of the room, preparatory to sumping the cutter bar for a new cut. In this position, the cable *a* impels the machine, with one component of its pull substantially along the cutter bar. The cable *b* is likewise anchored to a jack-post *j*, and the brake band 52 is set so that the swinging motion of the mining machine is just sufficient that the end of the cutter bar will progress forwardly substantially in line with the room rib, until the proper depth for the kerf is obtained.

In Fig. 16 the arrangement of the cables is shown for the turning of the machine to bring the cutter bar perpendicular to the room face, preparatory to traveling across the face, cutting the kerf. In Fig. 17 the machine is shown at any point as it travels across the room face, cutting the kerf. The cable *a* is wound onto the drum 12 to progress the machine and the cutter bar to the work of cutting the kerf, and the brake 52 will be set to regulate the paying off of the cable *b* at such rate as to keep the machine and the cutter bar parallel to the room face.

In Fig. 18 the machine is shown nearing the completion of the kerf cut, the cable *a* being reeved about the sheaves and hauling onto a jack-post placed to the rear and substantially parallel to the rib. The cable *b* will be controlled by proper slipping of the drum 38, so that the cutter bar will travel backwardly substantially parallel with the room rib.

In Fig. 19 the machine is shown hauling itself out of the room, or onto a mining machine carrier as may be desired.

From all the foregoing it will be understood that a mechanism has been provided constituting an exemplary embodiment of the invention, and realizing the objects and advantages herein set forth, together with other objects and advantages. It will be understood, further, that departures may be made from the exact mechanism as shown and described, within the scope of the accompanying claims, without departing from the principles of the invention and without sacrificing its chief advantages.

What I claim is:—

1. A mining machine including in combination a motor having a rotatable field and a rotatable armature, a kerf cutter, means for driving the kerf cutter from one of said rotatable motor elements, and means driven from the other of said rotatable motor elements for progressing the machine during the kerf cutting.

2. A mining machine including in combination a motor having a rotatable field and

a rotatable armature, a kerf cutter, means for driving the kerf cutter from one of said rotatable motor elements, and means driven from the other of said rotatable motor elements for progressing the machine during the kerf cutting, and means for maintaining the alignment of the machine with its work. 65

3. A mining machine including in combination a motor having a rotatable field and a rotatable armature, a kerf cutter, means for driving the kerf cutter from one of said rotatable motor elements, means driven from the other of said rotatable motor elements for progressing the machine during the kerf cutting, and means independent of the motor and cutter drive for maintaining the alignment of the machine with its work. 70

4. A mining machine including in combination a motor having a rotatable field and a rotatable armature, a kerf cutter, means for driving the kerf cutter from one of said rotatable motor elements, means driven from the other of said rotatable motor elements for progressing the machine during the kerf cutting, and means comprising a drum and brake for maintaining the alignment of the machine with its work. 85

5. A mining machine including in combination a motor having a rotatable field and a rotatable armature, a kerf cutter, means for driving the kerf cutter from one of said rotatable motor elements, and means driven from the other of said rotatable motor elements, and including braking device, for progressing the machine during the kerf cutting. 95

6. A mining machine including in combination a motor having a rotatable field and a rotatable armature, a kerf cutter, means for driving the kerf cutter from one of said rotatable motor elements, and means driven from the other of said rotatable motor elements, and including a cable drum and brake, for progressing the machine during the kerf cutting. 100

7. A mining machine including in combination a motor having a rotatable field and a rotatable armature, a kerf cutter, means for driving the kerf cutter from one of said rotatable motor elements, and means driven from the other of said rotatable motor elements, including a braking device and a cable drum rotated by said other rotatable motor element, for progressing the machine during the kerf cutting. 115

8. A mining machine including in combination a motor having a rotatable field and a rotatable armature, a kerf cutter, means for driving the kerf cutter from one of said rotatable motor elements, means for regulably applying additional resistance to the cutter driving means, and means driven

from the other of said rotatable motor elements for progressing the machine during the kerf cutting.

9. A mining machine including in combination a motor having a rotatable field and a rotatable armature, a kerf cutter, means for driving the kerf cutter from one of said rotatable motor elements, means comprising a brake drum and brake for regulably applying additional resistance to the cutter driving means, and means driven from the other of said rotatable motor elements for progressing the machine during the kerf cutting.

10. A mining machine including in combination a motor having a rotatable field and a rotatable armature, a kerf cutter, means for driving the kerf cutter from one of said rotatable motor elements, means for regulably applying additional resistance to the cutter driving means, and means driven from the other of said rotatable motor elements, and including braking devices, for progressing the machine during the kerf cutting.

11. A mining machine including in combination a motor having a rotatable field and a rotatable armature, a kerf cutter, means for driving the kerf cutter from one of said rotatable motor elements, means comprising a brake drum and brake for regulably applying additional resistance to the cutter driving means, and means driven from the other of said rotatable motor elements, and including braking devices, for progressing the machine during the kerf cutting.

12. A mining machine including in combination a motor having a rotatable field and a rotatable armature, a kerf cutter, means for driving the kerf cutter from one of said rotatable motor elements, means for regulably applying additional resistance to the cutter driving means, and means driven from the other of said rotatable motor elements, including a braking device and a cable drum rotated by said other rotatable motor element, for progressing the machine during the kerf cutting.

13. A mining machine including in combination a motor having a rotatable field and a rotatable armature, a kerf cutter, means for driving the kerf cutter from one of said rotatable motor elements, means comprising a brake drum and brake for regulably applying additional resistance to the cutter driving means, and means driven from the other of said rotatable motor elements, including a braking device and a cable drum rotated by said other rotatable motor element, for progressing the machine during the kerf cutting.

14. A mining machine including in combination a motor having a rotatable field and a rotatable armature, a kerf cutter, means

for driving the kerf cutter from one of said rotatable motor elements, and means for applying resistance to the other of said rotatable motor elements to govern the torque of the rotatable motor element driving the kerf cutter.

15. A mining machine including in combination a motor having a rotatable field and a rotatable armature, a kerf cutter, means for driving the kerf cutter from one of said rotatable motor elements, and braking means for applying resistance to the other of said rotatable motor elements to govern the torque of the rotatable motor element driving the kerf cutter.

16. A mining machine including in combination a motor having a rotatable field and a rotatable armature, a kerf cutter, means for driving the kerf cutter from one of said rotatable motor elements, and means for applying resistance to the other of said rotatable motor elements, including a brake and a brake drum rotating with said motor element, to govern the torque of the rotatable motor element driving the kerf cutter.

17. A mining machine including in combination a motor having a rotatable field and a rotatable armature, a kerf cutter, means for driving the kerf cutter from one of said rotatable motor elements, means for applying resistance to the other of said rotatable motor elements to govern the torque of the rotatable motor element driving the kerf cutter, and means driven from said other motor element for progressing the machine to the work during the kerf cutting.

18. A mining machine including in combination a motor having a rotatable field and a rotatable armature, a kerf cutter, means for driving the kerf cutter from one of said rotatable motor elements, means for applying resistance to the other of said rotatable motor elements to govern the torque of the rotatable motor element driving the kerf cutter, and means including a cable winding drum driven from said other motor element for progressing the machine to the work during the kerf cutting.

19. A mining machine including in combination a motor having a rotatable field and a rotatable armature, a kerf cutter, means for driving the kerf cutter from one of said rotatable motor elements, means for applying resistance to the other of said rotatable motor elements, including a brake and a brake drum rotating with said motor element, to govern the torque of the rotatable motor element driving the kerf cutter, and means driven from said other motor element for progressing the machine to the work during the kerf cutting.

20. A mining machine including in combination a motor having a rotatable field and a rotatable armature, a kerf cutter, means

for driving the kerf cutter from one of said rotatable motor elements, means for applying resistance to the other of said rotatable motor elements, including a brake and a 5 brake drum rotating with said motor element, to govern the torque of the rotatable motor element driving the kerf cutter, and means including a cable winding drum driven from said other motor element for 10 progressing the machine to the work during the kerf cutting.

21. A mining machine including in combination a motor having a rotatable field and a rotatable armature, a kerf cutter, 15 means for driving the kerf cutter from one of said rotatable motor elements, means for disconnecting the kerf cutter and its driving motor element, and means driven from the other of said rotatable motor elements 20 for progressing the machine during the kerf cutting.

22. A mining machine including in combination a motor having a rotatable field and a rotatable armature, a kerf cutter, means 25 for driving the kerf cutter from one of said rotatable motor elements, means for disconnecting the kerf cutter and its driving motor element, and means driven from the other of said rotatable motor elements, and including 30 braking devices, for progressing the machine during the kerf cutting.

23. A mining machine including in combination a motor having a rotatable field and a rotatable armature, a kerf cutter, means 35 for driving the kerf cutter from one of said rotatable motor elements, means for regulably applying additional resistance to the cutter driving means, means driven from the other of said rotatable motor elements for 40 progressing the machine during the kerf cutting, and means for disconnecting the kerf cutter from its driving motor element without disconnecting said resistance applying means.

45 24. A mining machine including in combination a motor having a rotatable field and a rotatable armature, a kerf cutter, means for driving the kerf cutter from one of said rotatable motor elements, means comprising a brake drum and brake for regulably applying additional resistance to the cutter driving means, means driven from the other of 50 said rotatable motor elements for progressing the machine during the kerf cutting, and means for disconnecting the kerf cutter from its driving motor element without disconnecting said resistance applying means.

55 25. A mining machine including in combination a motor having a rotatable field and a rotatable armature, a kerf cutter, means for driving the kerf cutter from one of said rotatable motor elements, means for regulably applying additional resistance to the cutter driving means, means driven from the other 60 of said rotatable motor elements, and includ-

ing braking devices, for progressing the machine during the kerf cutting, and means for disconnecting the kerf cutter from its driving motor element without disconnecting said resistance applying means. 70

26. A mining machine including in combination a motor having a rotatable field and a rotatable armature, a kerf cutter, means for driving the kerf cutter from one of said rotatable motor elements, and means for controlling the torque of said motor elements. 75

27. A mining machine including in combination a motor having a rotatable field and a rotatable armature, a kerf cutter, means for driving the kerf cutter from one of said rotatable motor elements, and means for applying resistance to said driving action to vary the torque of the other of said rotatable motor elements. 80

28. A mining machine including in combination a motor having a rotatable field and a rotatable armature, a kerf cutter, means for driving the kerf cutter from one of said rotatable motor elements, means driven from the other of said rotatable motor elements 90 for progressing the machine to the work during the kerf cutting, and means for applying resistance to the cutter driving connections to regulate the relative action of the kerf cutter and the machine progressing 95 means. 85

29. A mining machine including in combination a motor having a rotatable field and a rotatable armature, a kerf cutter, means for driving the kerf cutter from one of said rotatable motor elements, means driven from the other of said rotatable motor elements for progressing the machine during the kerf cutting, and reduction gearing between said 100 machine progressing means and its driving motor element. 105

30. A mining machine including in combination a motor having a rotatable field and a rotatable armature, a kerf cutter, means for driving the kerf cutter from one of said rotatable motor elements, and means driven from the other of said rotatable motor elements, and including braking devices, for progressing the machine during the kerf cutting, and reduction gearing between said 110 machine progressing means and its driving motor element. 115

31. A mining machine including in combination a motor having a rotatable field and a rotatable armature, a kerf cutter, means for driving the kerf cutter from one of said rotatable motor elements, means for applying resistance to the other of said rotatable motor elements to govern the torque of the rotatable motor element driving the kerf cutter, means driven from said other motor element for progressing the machine to the work during the kerf cutting, and reduction gearing between said machine progressing means and its driving motor element. 120 125 130

32. A mining machine including in combination a motor having a rotatable field and a rotatable armature, a kerf cutter and connections for driving it from one of said 5 rotatable motor elements, a braking device acting on said driving connections, means for disconnecting the kerf cutter beyond said braking means, a cable winding drum and connections for driving it from the other 10 of said rotatable motor elements, and braking means acting on said cable winding drum.

33. A mining machine including in combination a motor having a rotatable field 15 and a rotatable armature, a kerf cutter and connections for driving it from one of said rotatable motor elements, a braking device acting on said driving connections, means for disconnecting the kerf cutter beyond said 20 braking means, a cable winding drum and connections for driving it from the other of said rotatable motor elements, and braking means acting on said cable winding drum, a loose cable drum and a brake there- 25 for.

34. A mining machine including in combination a motor having a rotatable field and a rotatable armature, a kerf cutter and connections for driving it from one of said 30 rotatable motor elements, a braking device acting on said driving connections, a cable winding drum and connections for driving it from the other of said rotatable motor elements, and braking means acting on said 35 cable winding drum.

35. A machine including a motor having

a rotatable field and a rotatable armature, rotatable about a horizontal axis, a kerf cutter, driving means, rotatable about a vertical axis, for driving the kerf cutter, and connections for actuating said driving means from one of said rotatable motor elements, machine progressing means and connections for driving said progressing means from the other of said rotatable motor elements. 40 45

36. A machine including a motor having a rotatable field and a rotatable armature, kerf cutting means, driving means, rotatable about a vertical axis, for driving the kerf cutter and connections for driving said kerf 50 cutting means from one of said rotatable motor elements, machine progressing means and connections for driving said progressing means from the other of said rotatable motor elements, and means for maintaining 55 the machine in alignment with its work.

37. A machine including a motor having a rotatable field and a rotatable armature, work performing means and connections for driving said means from one of said rotatable motor elements, machine progressing means and connections for driving said progressing means from the other of said rotatable 60 motor elements, and devices for controlling the relative torque of said rotatable 65 motor elements to govern the relative action of the work performing means and the machine progressing means.

In testimony whereof, I have signed my name to this specification.

KENNETH DAVIS.
